UNITED STATES PATENT OFFICE

ARISTEDE A. THEODOROPULOS, OF NEW YORK, N. Y.

STOCKING-PROTECTING FOOTWEAR

Application filed April 4, 1928. Serial No. 287,217.

This invention relates generally to feminine clothing, and has more particular reference to novel elastic stockings for use as stocking protecting devices.

5 The invention has for an object the provision of a device of the class mentioned of simple durable construction, desirable and efficient in action, and which can be manufactured and sold at a reasonable cost.

10 The elastic protecting stockings are made from thin rubber provided with pretty ornamental designs on the outer sides. In addition to protecting one's stockings, these protectors also serve the purpose of keeping the wearer's legs warm and dry. They readily assume the shape of the wearer's legs, looking 15 stylish. The ornamental designs on the outer sides may be brilliantly colored. A pair of protectors can easily be rolled up into a package no larger than a cigarette case and thus carried conveniently in a lady's bag, so as to be handy for use in the event the weather changes for sudden rains or snow. At the upper ends the protectors are provided with 20 bands to permit rolling downwards of the upper material to vary the heights of wearing. The lower ends are designed to engage the foot beneath a wearer's shoe. A holding strap is arranged adjustably in regards to 25 positions so as to be movable to engage beneath the arch of a wearer's foot.

For further comprehension of the invention, and of the objects and advantages thereof, reference will be had to the following description and accompanying drawings, and to the appended claims in which the various features of the invention are more particularly set forth.

Referring to the accompanying drawing, 30 forming a material part of this disclosure:—

Fig. 1 is a fragmentary side view of a wearer's leg with a stocking protector engaged thereon, and a shoe on the foot of said leg.

Fig. 2 is a similar view, but showing a modified form of protector constructed according to the same invention.

Fig. 3 is a side view of a protector with the top thereof partially turned inside-out and constructed according to the same invention.

Fig. 4 is a view similar to Fig. 3, but show-

ing another form of protector constructed according to the same invention.

Fig. 5 is a sectional view, taken on the line 5—5 of Fig. 4.

Fig. 6 is a horizontal sectional view, taken 65 on the line 6—6 of Fig. 4.

The reference numeral 10 indicates generally a wearer's leg provided with a stocking protector 11 and a shoe 12.

The protector 11 consists of a knee portion 60 13, a calf portion 14 and a foot portion 15. A plurality of loop stitches 16 engage the knee portion 13 and a garter 17 is secured in place by these stitches. A band 18 is attached to the very top of the knee portion, and serves 65 as a starter for rolling the protector downwards on the leg. Ornamental designs 19, 19' and 19^a are formed on the outside of the protector 11. The foot portion 15 consists of a fragmentary heel covering portion 20, 70 and an arch strap 25. The protector 11 is lined on the inside with a lining of camel's hair 22.

The foot portion 15 has a pair of strings 23 75 extended along opposite edges, and held against displacement at their ends 24 so that the strings are free along their lengths. The arch strap member 25 has its ends slidably connected with the strings so as to be movable along the lengths of the strings. A plurality of strings 26 are attached to the foot portion 15 along the length of the strings 23. Other strings 27 are attached to the arch strap 25. In operation, the arch straps 25 are moved along the strings 23 to a position to best 80 accommodate a wearer's arch. Then the strings 27 of the arch straps are tied to the nearest strings 26 of the foot member 15 so as to hold the arch member as positioned.

While I have shown and described a preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:—

1. An elastic stocking protector compris. 100

ing a protector member having a foot portion, a pair of strings extended along opposite edges of the foot portion, and attached at their ends to the foot portion, an arch strap having its ends slidably connected to the said strings so as to be movable along the lengths of the strings, a plurality of strings attached to the foot portion along the lengths of the first mentioned strings, and other strings attached to the arch strap, and tied to the nearest strings of the second mentioned strings so as to hold the arch member as positioned along the first mentioned strings.

2. An elastic stocking protector, comprising a protector member having a foot portion, an arch strap slidably mounted at its ends along the edges of the foot portion, a plurality of strings attached on the foot portion, and other strings attached on the arch strap, and tied to the nearest strings on the said foot portion so as to hold the arch member as positioned along the edges of the foot portion.

In testimony whereof I have affixed my signature.

25 ARISTEDE A. THEODOROPULOS.
